Primary Examiner — Philip S Hyder(74) *Attorney, Agent, or Firm* — Merchant & Gould P.C.(57) **CLAIM**

The ornamental design for a hammer as shown and described.

DESCRIPTION

FIG. 1 is a right-side perspective view of a hammer, showing the new design;

FIG. 2 a right-side elevation view of the hammer shown in FIG. 1;

FIG. 3 is a left-side elevation view of the hammer shown in FIG. 1;

FIG. 4 is a top plan view of the hammer shown in FIG. 1; FIG. 5 is a bottom plan view of the hammer shown in FIG. 1;

FIG. 6 is a rear elevation view of the hammer shown in FIG. 1; and,

FIG. 7 is a front elevation view of the hammer shown in FIG. 1.

The broken lines depict aspects of the hammer in which the design is embodied that form no part of the claimed design.

1 Claim, 2 Drawing Sheets(56)
